WILLIAM SANDERSON, OF NEW YORK, N. Y.

Letters Patent No. 65,952, dated June 18, 1867.

IMPROVEMENT IN CUTLERY.

The Schedule referred to in these Letters Patent and making part of the same.

TO ALL WHOM IT MAY CONCERN:

Be it known that I, WILLIAM SANDERSON, of New York, New York county, in the State of New York, have invented a new and useful Improvement in Handles of Knives, Forks, &c.; and I do hereby declare that the following is a full and exact description thereof, reference being had to the accompanying drawings, making part of this application.

My invention relates to a new method of making the handles of knives and forks and other analogous instruments, and has for its main object to produce a handle which will be stronger, more durable, and more economic of manufacture than any heretofore made, and to these ends my invention consists in forming the handle of a knife or other instrument of a metallic frame solid with the bolster, and attaching to each side of said frame metallic scales, substantially as hereinafter more fully described.

To enable those skilled in the art to make and use my invention, I will proceed to describe it more fully, referring by letters to the accompanying drawings, in which—

Figure 1 is an elevation or side view of a table-knife made in accordance with my invention.

Figure 2 is a similar view, showing the handle with one of its scales or side-pieces removed, to illustrate clearly the form of the metallic frame or body of the handle.

Figure 3 is a cross-section at the line x x , fig. 2; and

Figure 4 is a similar section, showing a different form or shape of handle.

Figs. 3 and 4 are exaggerated in size, to more clearly show the shape of the parts.

A is the blade, B the handle of the knife, and C its bolster. The blade A may be made of fine steel, and welded, soldered, or otherwise securely attached to the bolster C. The frame d I propose to cast solid with the bolster C of malleable iron or any other desirable metal, and of the peculiar form shown, with rebates or depressions running round its edges, into which fit the edges of the metallic "scales" or side-pieces B, (see figs. 2, 3, 4.) These scales I propose to strike up out of sheet metal of any desired pattern or design, corresponding in contour with the frame d, and solder or otherwise securely attach them to the said frame d. The handle shown at figs. 1, 2, and 3 is so shaped as to be about rectangular in cross-section, but the frame may be cast convex on its outer edge, as seen at e, fig. 4, and the scales may be struck up of the shape seen at B', fig. 4, so that the cross-section of the handle will present in form an ellipsis or oval. It will be understood that the scales may be made of any desired design, and that the frame d (e) may be cast of any desired shape. In the manufacture of a cheap article, the handle constructed as already described may be japanned, and to make a higher finished article it may be silver or gold plated. It will be seen that while my new construction of handle is adapted to every variety of form and style of finish, it is always extremely strong and durable, and is easily made. In lieu of casting the frame and bolster solid, as I have shown it, the frame d might be rolled or otherwise formed out of a separate piece, bent into shape, and its ends welded or otherwise rigidly attached to the bolster; but it will be evident that such a mode of manufacture, if it produced the bolster and frame united in a solid manner, would be equivalent almost to a handle made or cast solid; and though I do not deem such a process of manufacture as desirable as that I have hereinbefore explained, I consider it no substantial departure from the spirit of my invention. It is well known that in the ordinary method of manufacture of knife and fork handles with a tang extending from the bolster, and with scales of wood, ivory, and other material riveted on each side of said tang or shank, the scales shrink and leave the tang, and often crack off, and it will be seen that, by my new method of constructing or making a handle, I can produce an article perfectly durable, very strong, and very cheap, if desired.

Having fully described my improved method or mode of making handles of knives, forks, &c., so that those skilled in the art can understand the same, what I claim as new, and desire to secure by Letters Patent, is—

A handle formed of a metallic frame, (cast with or rigidly united to the bolster,) and scales, or side-pieces, substantially as described.

In testimony whereof I have hereunto set my hand and seal this third day of April, 1867.

WM. SANDERSON. [L. S.]
